UNITED STATES PATENT OFFICE.

HENRY SKARL, OF CLEVELAND, OHIO.

PISTON-PACKING.

1,395,603.

Specification of Letters Patent. Patented Nov. 1, 1921.

Application filed March 28, 1921. Serial No. 456,282.

To all whom it may concern:

Be it known that I, HENRY SKARL, a citizen of the United States, residing at Cleveland, in the county of Cuyahoga and State of Ohio, have invented new and useful Improvements in Piston-Packings, of which the following is a specification.

This invention relates to packing for pistons and while it is designed primarily for use in connection with internally explosive engines, it is understood that it may be used in connection with any mechanism in which a movable piston is fitted within a cylinder.

As is well known, the piston of an internal explosive engine is provided with any number of circumscribed grooves in each of which is disposed an open expansive ring.

It is found in practice that in the use of the ordinary type of ring there is a loss of compression by reason of the gas escape not only through the joint of the ring but also through the grooves of the piston, along the sides of the ring and under the ring. By the same token excessive oil works past the rings into the combustion chambers. It is therefore highly important that not only shall the ring fit snugly with its outer periphery against the inner wall of the cylinder and that the ring ends be in close contact, but also that the rings transversely fit the piston grooves so as to be in gas excluding contact with the side walls of the piston grooves. It is equally important that the rings be capable of rapidly accommodating themselves to any inequalities in the surface of the cylinder due to wear or similar defects.

It is the object of the present invention to form a packing that will prevent gas escape through the joint ends, along the sides of the packing, also, in and around the back of the packing. To this end the ring has been designed to rapidly accommodate itself to the cylinder and fit snugly transversely in the piston groove.

The invention consists of the novel features of construction hereinafter described and particularly pointed out in the claims.

The accompanying drawings illustrate certain embodiments of the invention.

Figure 1, is a side elevation of the piston packings in place on the piston head.

Fig. 2, is a side elevation of the ring, with a side elevation of the inner spring steel follower ring, part of the outer wear mem-

ber being broken away to give a cross section view of the internal construction of the ring and the quick seating facilities on the outer periphery.

Fig. 3, is a detailed view in cross section of the packing shown in Fig. 1.

Fig. 4, is a perspective view showing the composite packing cut in two with its resultant parts in different planes.

Heretofore it has invariably been the practice to make the packing the same width transversely as the piston groove, likewise having a greater normal outside diameter than the inside diameter of the cylinder. This condition has been adhered to in the new invention.

In the ordinary type of ring there is a slight distortion when the ring is pressed into the cylinder so that the ring does not make a true fit; in the new invention the center of the outer periphery of the ring is somewhat lower than at the edges, the high points being very thin wear away quickly thereby enabling a true fit all around the inner circumference of the cylinder.

Referring to the drawings: A represents the cylinder, P the piston, D the circumscribed grooves in which the packing is disposed.

In the forms shown in Fig. 1 the packings consist of suitable rings B divided at a single point b, but otherwise continuous.

The ring is resilient and expands into contact with the cylinder bore by its own resiliency. The cut b is made with a lap joint, the two steps of the joint overlapping when the ring is in place, thereby preventing any direct leakage through the cut.

The inner side of the ring B is made partly straight (parallel to the outer wearing face) and partly with an inward facing bevel b'.

The width of the ring is preferably the same width as that of the circumscribed grooves D. By having this arrangement the use of a ring compressor is practically eliminated. Where the width of the ring is less than that of the grooves a compressor is invariably required when the rings are forced into the cylinder.

Referring to Fig. 2, E is the concaved surface on the outer periphery of the member B, the concavity being a radius and coming almost to the edges. The edges being thin will wear off rapidly causing a snug fit all around the inner wall of the cylinder, regardless of wear or similar irregularities in

said cylinder. Where the outer periphery is straight across the face, the volume of metal to be worn away being great, a considerable length of time is required for the 5 ring to adapt itself to a worn or irregular cylinder.

C is a spring follower ring divided at a single point c and normally tending to expand by its own resiliency.

- 10 The follower ring is made of thin, flat rolled spring steel considerable less in width than the member B, the normal outside diameter of member C being considerably greater than the inside diameter of member 15 B. The member C is rolled and pressed with a bevel to conform to the bevel b' on the member B, as the normal outside diameter of member C being greater than the normal inside diameter on B, the follower 20 C acting on the bevel surface b', by reason of its own expansion, exerting a constant pressure tends to force itself against one of the sides of groove D thereby compensating for any inequalities between groove D 25 and the member B caused either through wear or otherwise on either one or both groove D and the ring B. Thus the packing is maintained tight against loss of pressure underneath the ring, between the ring and 30 the piston.

The follower ring C is preferably made of thin flat rolled spring steel, as this is substantially the cheapest and surest method of securing an accurate follower ring. The 35 metal being thin, will by its own resiliency press outward and conform to the corresponding bevel b'; the thin lower edge tightly hugging the side of the groove D, yet the pressure exerted being insufficient 40 to cause grooving of the ring C in the sides of groove D.

Where a machined follower ring is used great care must be exercised in accurately machining both the bevel on the inside of 45 the wear member and the corresponding bevel on the follower ring.

Where a round wire follower ring is used, even if ground flat on the side adjacent to the side of the circumscribed piston groove, 50 it yet presents but a mere line contact on the outer radius with the bevel on the inner side of the wear member. When the wear member is considerably less in width than the width of the piston groove, there is a

slight creeping movement of the ring with 55 the up and down movement of the piston, thereby causing the round periphery of the follower ring to embed itself into the bevel, frequently causing a short lived ring as there being wear on both sides of the ring. 60

I claim:

1. In combination a piston having one or more circumscribed grooves therein and a packing ring in said groove or grooves comprising a continuous resilient packing ring 65 divided at a single point and having a partly cylindrical and a partly conical surface at its inner side, said packing being substantially the same in width as the width of the groove in which it is disposed, and a flat 70 rolled spring steel follower ring rolled and pressed into beveled form engaging the beveled surface on the inner side of the outer packing pressing outward and downward 75 engaging one of the sides of the circumscribed groove in the piston.

2. In combination a cylinder, a piston loose within the cylinder and having one or more circumscribed grooves therein and a packing in said groove or grooves, divided 80 at a single point with a lap joint, having a partly cylindrical and a partly conical surface on its inner side, the outer face of said packing being concave, the normal outside diameter of said ring being substantially 85 greater than the inside diameter of the cylinder, the said ring being forced outward against the cylinder wall by its own resiliency, said packing ring being substantially the same in width as that of the groove 90 in which it is disposed, and a spring steel follower ring made of thin, flat rolled annealed spring steel, said follower ring being rolled and formed with a bevel to engage the beveled surface on the inner side of the outer 95 ring, the normal outside diameter of the follower ring being substantially greater than the normal inside diameter of the outer ring and expanding into position by its own resiliency. 100

In testimony whereof I have hereunto set my hand in presence of two subscribing witnesses.

HENRY SKARL.
